(57) **CLAIM**

The ornamental design for drum plug with overcap retainer groove, as shown and described.

DESCRIPTION

FIG. 1 is a top perspective view of the drum plug with overcap retainer groove showing our new design;

FIG. 2 is a top plan view thereof;

FIG. 3 is a side view thereof;

FIG. 4 is a bottom view thereof; and,

FIG. 5 is a sectional view thereof, taken on line 5-5 of FIG. 2.

The broken lining shown in the drawings depicts portions of the article that form no part of the claim.
